UNITED STATES PATENT OFFICE.

JOSEE JOHNSON, OF NORFOLK, VIRGINIA, ASSIGNOR TO HIMSELF AND HOLLOWAY P. EMBURY, OF SAME PLACE.

PEANUT-CLEANER.

SPECIFICATION forming part of Letters Patent No. 311,495, dated February 3, 1885.

Application filed April 15, 1884. (No model.)

To all whom it may concern:

Be it known that I, JOSEE JOHNSON, of Norfolk, in the county of Norfolk and State of Virginia, have invented certain new and useful 5 Improvements in Peanut-Cleaners; and I do hereby declare that the following is a full, clear, and exact description thereof, reference being had to the accompanying drawings, and to the letters of reference marked thereon, which form 10 part of this specification.

This invention relates to machines for cleaning, separating, and grading peanuts; and it has for its objects to provide a machine which shall possess superior advantages in point of 15 simplicity, durability, and general efficiency.

To this end it consists in the improved construction and arrangements of parts, which will be hereinafter fully described, and particularly pointed out in the claims.

20 In the drawings hereto annexed, Figure 1 is a longitudinal sectional view of my improved peanut-cleaner. Fig. 2 is cross-section taken on the line *x-x* in Fig. 1. Fig. 3 is a detail view of one of the separating-partitions. Fig. 4 is a 25 detail view of the adjustable partitions straddling the bottom of the casing; and Fig. 5 is a side view of the machine, showing the picking-table.

The same letters refer to the same parts in 30 the several figures.

A in the drawings refers to the box or casing, which is preferably of a rectangular shape and provided with a bottom, B, which is made to slant or incline to both sides of the casing, where 35 doors C are provided that do not extend entirely to the edges of the said inclined sides, but leave narrow slits or openings D for the escape of the nuts, as will be hereinafter more fully stated.

40 Arranged at the front end of the casing A is the fan-case E, the sides of which are provided with slides F for the purpose of regulating the admission of air. The fan-case is constructed with an opening, G, in rear of which an inclined 45 deflector, H, is placed, and said opening may be closed by means of a flexible slide, I, constructed of sheet metal or other suitable material, and for the accommodation of which a passage, J, is provided in the upper and rear part 50 of the fan-case. The front side of the said fan-case is constructed with a supplementary pas-

sage, K, taking air through an opening, L, from the interior of the casing and terminating in a blast-opening, M, a short distance below the opening G and deflector H. A flexible slide, 55 N, of sheet metal or other suitable material, is provided, whereby the opening L may be partly or entirely closed, and by which the force of the blast through the supplementary passage K may be regulated. The regulating-slides are 60 of course conveniently accessible to an operator stationed in front of the machine. The hopper O is provided on one side with a slide-valve, P, for regulating the feed, and in the throat of this hopper is a corrugated feed-roller, which 65 may receive rotation from the fan-shaft by means of pulleys and a belt.

S is an inclined partition, arranged longitudinally in the casing and extending from the fan-case to the rear end of the main casing, as shown 70 in the drawings. This partition, which may be arranged to slant to either side of the main casing, is arranged above the blast-opening M and diagonally across the deflector H, so that nuts blown off the latter will be thrown upon the said 75 partition S, while the heaviest and best of the nuts will drop upon the bottom of the casing. The partition S is provided at its lower edge with a series of escape-openings, T T, between which partitions U are arranged. The upper 80 edges of these partitions may be provided with hinged gates V, for the purpose of regulating and modifying the blast, and hence intercepting the various grades of nuts as they are blown through the box or casing. 85

The sides of the box or casing are provided with hinged picking-tables W W, adjustable by means of rods, cords w, or in any suitable manner, so as to be set at any desired inclination, and provided with flanged openings X, 90 through which the refuse may be thrown.

Arranged upon the double slanting or inverted-V-shaped bottom of the casing A is a partition, Y, consisting of a saddle, Z, straddling the said bottom, and to which is attached 95 a board, A', having a horizontal upper edge and terminating some distance below the fan-case. This partition is capable of being adjusted longitudinally to any desired extent. The top of the casing A has a longitudinally-sliding cover, C', which, when closed, leaves a narrow opening or slit at the rear end of the

box for the escape of the blast and of such particles of dust as may be removed from the nuts by the blast.

Benches D' are arranged under the picking-tables in the manner and for the purpose set forth and claimed in my application for Letters Patent for improvements in peanut-cleaners of even date with the present application, Serial No. 127,974.

- 10 From the foregoing description, taken in connection with the drawings hereto annexed, the operation and advantages of this invention will be readily understood. The peanuts passing from the hopper drop upon the inclined 15 wind-board or deflector in rear of the fan-case. At this point they encounter the first blast coming through the opening G, by which the light and otherwise defective nuts are blown over the deflector and into the upper part of 20 the casing above the floor or partition S, where in passing through the machine they successively encounter the several partitions, U U, by which the several grades of nuts are intercepted and deflected through the escape-openings T. The best and heaviest nuts, which are 25 not blown over the wind-board or deflectors, will be dumped from the latter upon the inverted-V-shaped bottom of the machine, encountering in the passage the second blast 30 coming through the opening M of the fan-case. The heaviest and most superior nuts will thus be dropped in front of the partition Y, and those that are somewhat lighter in rear of the said partitions, which latter may be moved or 35 adjusted so as to grade or separate the product in any desired manner. The nuts, having thus been separated, pass to the picking-tables, where attendants are stationed for the purpose of removing the black and rotten 40 nuts, which are thrown through the openings in the picking-tables, and thence conveyed to some suitable receptacle or place of deposit.

Having described my invention, I claim—

1. In a peanut-cleaner, the combination, with a box or casing, of a fan, a fan-case having a blast-opening, G, and a passage, J, an inclined deflector arranged in rear of the same, and an adjustable slide, I, arranged in said passage, substantially as described. 45

2. In a peanut-cleaner, the combination, with the box or casing and the hopper, of the fan, a fan-case having blast-openings directed beneath the discharge from the hopper, the flexible slides, and the deflector H, substantially as described. 50

3. In a peanut-cleaner, the combination, with a casing having a V-shaped bottom, and a fan-case having separate and independent blast-openings, one of said openings, L M, communicating with said V-shaped bottom, of an inclined deflector, and a longitudinal inclined partition, substantially as set forth. 60

4. The combination, in a peanut-cleaner, of a casing having a V-shaped bottom, a fan-case having separate and independent blast-openings, one of said openings, L M, communicating with said V-shaped bottom, an inclined deflector, an inclined longitudinal partition, and a series of transverse partitions, substantially as set forth. 65

5. In a peanut-cleaner, the combination of a box or casing having an inverted-V-shaped bottom, a fan-case having two separate and independent blast-openings, an inclined deflector, an inclined longitudinal partition having escape-openings at its lower edge, and a partition straddling and longitudinally adjustable upon the inverted-V-shaped bottom of the casing, substantially as set forth. 75

In testimony that I claim the foregoing as my own I affix my signature in presence of two witnesses.

JOSEE JOHNSON.
